UNITED STATES PATENT OFFICE.

THOMAS HOLT, OF WALSHAW, BURY, ENGLAND.

MANUFACTURE OF WOVEN FABRICS.

1,166,211.

Specification of Letters Patent. Patented Dec. 28, 1915.

Application filed July 19, 1912. Serial No. 710,479.

To all whom it may concern:

Be it known that I, THOMAS HOLT, a subject of the King of Great Britain and Ireland, residing at Victoria Mills, Walshaw, 5 Bury, county of Lancaster, England, cotton manufacturer, have invented Improvements in the Manufacture of Woven Fabrics, of which the following is a specification.

This invention relates to improvements in 10 the manufacture of quilts or bed spreads. In this invention the quilt is woven with one coarse weft and two coarse warps which are preferably of finer counts than the weft; the warps used are of equal counts, but the cloth 15 may be woven with warps of unequal counts.

In this invention one of the warps known as the back warp, contains only half the 20 number of ends contained by the other warp, which is known as the face warp, that is, one third of the yarn comes from the back warp and the remaining two thirds comes from the 25 face warp. The back warp is heavily weighted and the face warp lightly weighted, thus giving the groundwork of the quilt a ribbed appearance.

For the ground weave of the quilt all the 30 face warp is lifted and all the back warp is left down on odd numbered picks, and all the back warp is lifted and the face warp left down on even numbered picks.

For the figure weave all odd numbered 35 picks are the same as for the ground weave, but on even numbered picks those threads which are required to figure are lifted up; these threads come from the face warp, and at the same time all the back warps are lifted. The back warp is drawn in through 40 healds, which are worked by a tappet, while the face warp is drawn through mails and worked by a jacquard. The mails are knotted above the comber boards, and these lift on all odd numbered picks, while the jacquard for figuring purposes lifts on even numbered picks. Two threads from the face 45 warp and one thread from the back warp are drawn in each dent of the reed. Two threads from the face warp may also be drawn through each mail, and thus allow a mounting to be used containing only half the number of mounting threads compared to the 50 threads in the face warp.

On the accompanying drawing Figure 1 represents the order of lifting for the ground weave of cloth, Fig. 2 represents the order 55 of lifting for the figure weave of cloth (the

eighth pick shows the ground weave), Fig. 3 is a section of cloth showing end view of the weft threads and the method of interlacing for figure and ground weave, Fig. 4 represents section of cloth on all odd numbered picks showing an end view of the warp threads, Fig. 5 is a section of cloth on even numbered picks showing a part as figure weave and a part as ground weave and is an end view of warp threads.

Having thus described my invention, what I claim as new and desire to secure by Letters Patent is:—

1. A raised-warp figured fabric having a single coarse weft and finer face and back warps, of which the face is composed of twice as many ends as said back warp; the fabric having a ribbed ground showing alternately at the back and front thereof and formed by all the ends of the face warp passing over the weft and all the ends of the back warp passing under the weft on all odd numbered picks, and all the ends of the face warp passing under the weft and all the ends of the back warp passing over the weft on 80 all even numbered picks; the raised figures being formed by the ends of the face warps floating over the weft for a number of picks, and the ends of the back warp at such figures continuing to pass collectively under and 85 over the weft picks upon which the face warp is floated.

2. A raised-figured fabric having a single coarse weft; and face and back warps, of which the face warp is composed of a greater number of threads than said back warp, the fabric having a ribbed ground formed by all the raised ends of the face warp and showing alternately at the front and the back thereof, all the ends of the back warp being left 95 down on all odd numbered picks, and all the ends of the face warp being left down while all the ends of the back warp on even-numbered picks are lifted; the raised figures being formed by floating the ends of the face 100 warp over the wefts for a number of picks and the ends of the back warp at such figure continuing to pass collectively under and over the weft picks upon which the face warp is floated.

3. A raised-figured fabric having a single coarse weft; and face and back warps of which said face warp is composed of twice as many threads as said back warp, the fabric having a ribbed ground formed by all 110

the raised ends of the face warp and showing alternately at the front and the back thereof, all the ends of the back warp being left down on all odd-numbered picks and all the ends of 5 of the face warp with all the ends of the back warp on even-numbered picks being left up; the raised figures being formed by floating the ends of the face warp over the wefts for a number of picks and the ends of 10 the back warp at such figure continuing to

pass collectively under and over the weft picks upon which the face warp is floated.

In testimony whereof, I have signed my name to this specification, in the presence of two subscribing witnesses.

THOMAS HOLT.
